UNITED STATES PATENT OFFICE.

MAUDE SIEGEL, OF NEW YORK, N. Y., ASSIGNOR TO FRANKLIN SIMON & CO. INC., OF NEW YORK, N. Y., A CORPORATION OF NEW YORK.

DESIGN FOR A DRESS.

Application filed July 15, 1924. Serial No. 10,157. Term of patent 3½ years.

To all whom it may concern:

Be it known that I, MAUDE SIEGEL, a citizen of the United States, and a resident of the city of New York, borough of Manhattan, in the county and State of New York, have invented a new, original, and ornamental Design for Dress, of which the following is a specification, reference being had to the accompanying drawing, forming part thereof, wherein the dress is distinguished by the decided tunic effect with spaced circumferentially-extending tucks in the lower part and spaced longitudinally-extending tucks in the upper part. The dress is also distinguished by buttons extending from the

center of the neck opening downwardly to the first circumferential tuck and on each side from the bottom upwardly to about the waist-line.

Figure 1 is a perspective view showing the front and part of one side of a dress, disclosing my new design.

Figure 2 is a perspective view of the rear part of one side of the dress shown in Figure 1.

I claim:

The ornamental design for a dress, substantially as shown and described.

MAUDE SIEGEL.
